FIG.4

FIG.6

FIG.5

FIGURE 1 is an elevational view of one side of a book box combination chair-desk embodying our new design; FIGURE 2 is an elevational view of the other side thereof;

FIGURE 3 is a front elevational view thereof; FIGURE 4 is a rear elevational view thereof; FIGURE 5 is a bottom plan view thereof; and FIGURE 6 is a front elevational view of the unit of FIGURE 1 wherein the legs are tapered adjacent their lower ends instead of straight.

The dominant features of our design reside in those portions shown in full lines in the drawings.

We claim:

The ornamental design for a book box combination chair-desk, substantially as shown and described.
